ATTORNEY

UNITED STATES PATENT OFFICE.

HUGO SOHMER, OF NEW YORK, N. Y.

PIANO-ACTION.

SPECIFICATION forming part of Letters Patent No. 268,563, dated December 5, 1882.

Application filed June 1, 1882. (No model.)

To all whom it may concern:

Be it known that I, HUGO SOHMER, of the city, county, and State of New York, have invented certain new and useful Improvements 5 in Upright-Piano Actions, of which the following is a specification.

This invention relates to an improved upright-piano action, by which a quick and absolutely certain repetition is obtained; and the 10 invention consists of a hammer-butt having an elbow-shaped arm, with a spring-pressed flange pivoted to the lower end of the arm and suspended therefrom by a hook, said flange extending forward toward the butt and the actuating-jack.

In the accompanying drawings, Figures 1 and 2 represent side views of my improved upright-piano action, showing it respectively in a position of rest and in action.

20 Similar letters of reference indicate corresponding parts.

In the drawings, A A' A² represent the supporting-frame of my improved upright-piano action; B, the hammer; C, the butt, and D the 25 fulcrumed and spring-acted jack, which is operated by the key and suitable transmitting mechanism in the usual manner. The jack D acts upon the lower part of the butt and causes thereby the hammer to strike the string. To 30 the rear part of the butt is applied a fixed elbow-shaped arm, C', to which is hinged a spring-pressed flange, E, said flange being hung by a hook, e, to the arm C', as shown clearly in Figs. 1 and 2. The flange E extends from the end 35 of the arm C' forward toward the rear part of the butt C, and forms a stop or cushion for the jack D as soon as the same is raised, so as to lift the hammer butt, as shown in Fig. 2. The effect of the flange E on the jack D is to limit

the motion of the latter and to produce the 40 short stopping of the same. The flange E is connected by a bridle, f, in the usual manner, with an arm, g, of the oscillating lever to which the jack is fulcrumed. The bridle f returns the hammer against its check in the usual 45 manner. As the motion of the jack D is confined and limited by the interposition of the flange E the jack is prevented from leaving the butt farther than necessary for the relief of the hammer from the string, while the cushioning-spring of the flange E enables the jack to adjust itself automatically to any degree of force which is exerted on the key. The limited motion of the jack D, combined with the receding of the flange E in response to the greater 50 or less force exerted upon the key and jack, admits of the quick and absolutely certain repetition of the action, without requiring the full return of the key to its normal position.

Having thus described my invention, I claim 55 as new and desire to secure by Letters Patent—

In a repeating action for upright pianos, the combination of a jack, D, hammer-butt C, having an elbow-shaped arm, C', and a spring-pressed flange, E, pivoted to the lower end of 60 the arm C' and suspended therefrom by hook e, said flange extending forward into close proximity with the butt C and jack D, substantially as set forth.

In testimony that I claim the foregoing as 70 my invention I have signed my name in presence of two subscribing witnesses.

HUGO SOHMER.
